JOHN H. IRWIN, OF PHILADELPHIA, PENNSYLVANIA.

Letters Patent No. 89,584, dated May 4, 1869.

IMPROVEMENT IN THE MODE OF GUIDING VELOCIPEDES ON A SINGLE TRACK.

The Schedule referred to in these Letters Patent and making part of the same.

To all whom it may concern:

Be it known that I, JOHN H. IRWIN, of Philadelphia, in the county of Philadelphia, and State of Pennsylvania, have invented a new and useful Mode of Controlling Carriages Upon a Single Track; and I do hereby declare the following to be a full, clear, and exact description of the same, reference being had to the accompanying drawings, in which—

Figure 1 is a side elevation of an apparatus exhibiting my invention.

Figure 2 is a plan of the same.

Figure 3 is a front elevation of the same.

Figure 4 is an elevation of one of the adjustable boxes.

Figure 5 represents carriages constructed for conveyance of goods or passengers, and controlled by the same means.

In this specification I employ the terms "bicycle" and "velocipede" in a conventional sense, and for convenience only, and by those terms I intend to be understood as referring to any vehicle or carriage with two or more wheels arranged in a single plane, so that one follows in the track of another, and propelled by any available power, whether the same be mechanical or animal.

This invention relates to a bicycle-velocipede, adapted to run upon a track composed of a single rail; and

It consists in mechanical means provided to enable the rider to insure his balance while unable to vary the direction of the line of progression.

Hitherto, the rider on a bicycle-velocipede could only maintain the equilibrium of his body by moving the same from side to side, or by varying the line of progression from side to side, as may be necessary to restore said equilibrium. That is to say, when the rider's body inclines to one side, so as to remove the centre of gravity toward one side of the line of bearing upon the ground, said line is shifted so as to be again beneath the centre of gravity, by changing the direction of the steering-wheel.

This operation of balancing is well understood, but is manifestly impossible if the vehicle is confined to a single line of progression, as would be the case in running upon a single rail or track. I therefore apply a mechanical auxiliary, by means of which the rider may maintain his equilibrium without moving his seat; and this mechanical auxiliary consists,

First, in a counter-weight under control of the rider, which may be projected on one side of the line of progression when the weight of the rider inclines to the opposite side; and

Second, in the power of a lever, in addition to the counter-weight above referred to.

Mechanically, the counter-weight might be applied as in the balancing-pole of a rope-dancer, but practically that mode of application is not feasible, because of the space which it would be required to occupy. I have therefore placed my counter-weight upon the same track, and upon independent wheels, but con-

nected to the main bicycle by a connection which places the vertical position of said counterpoise under control of the rider.

From the above, it will be understood that I do not limit myself to any particular mode of applying the mechanical counterpoise, which shall enable the rider to maintain his equilibrium without moving his body for that purpose, but I describe and show in this patent only the elements of a mode which experiment has convinced me to be the most satisfactory.

Having now set forth the nature and principle of my invention, I will particularly describe the construction of a velocipede to which it is applied in a practical form.

The wheels, A B, of a velocipede are mounted in, and support a suitable frame, C, and seat, D, for the rider.

In this case the front wheel, A, is not intended to turn upon a swivel, for the purpose of steering, but it always continues to revolve in the same plane with the wheel B. If desired, however, it may in fact be constructed so that it can be adjusted to swivel, and thus be capable of use like the ordinary two-wheeled velocipede.

The cranks E E form the means of connection between the propelling-power and the driving-wheel of the velocipede.

For the purpose of being propelled upon a single rail, as upon a railroad-rail, the wheels should all be flanged on both sides.

The counterpoise in this case is represented in the small truck F, mounted on wheels similar to the wheels A B. This truck travels upon the rail or track pursued by the main bicycle, and preferably in advance thereof, as shown.

The small truck F is connected to the main bicycle by the connecting-rod G, which is provided with suitable joints at each of its ends, and also a swivel at one end, so that it may freely conform to all possible changes in the relative positions of the two carriages.

The rear end of the connecting-rod G is provided with a hand-lever, H, by means of which the rod G is controlled, and the equilibrium of the apparatus maintained, and the mode and principle of the operation of the counterpoise-truck F will be fully and clearly understood by reference to fig. 3, in which are shown the relative positions of the velocipede and the counterpoise-truck when the equilibrium of the former is disturbed by an inclination to one side.

This action of the counterpoise F is under control of the rider, who thus counteracts a tendency of his own body to fall over to one side.

When the wind chances to be favorable, the small sail I may be employed, and steam-power may also be used, if desired, to propel the vehicle.

Fig. represents a train of carriages connected and controlled in the manner and upon the principles of the apparatus herein described. The propelling-power is not shown in fig. 5, but the same may be mechani-

cal, and applied in advance, upon the same track, or it may be located within one of the carriages, or it may be animal power, applied in the usual way.

The lever at the top of the carriages not only forms the connection between them, but enables the steersman to control the relative positions of the carriages, which, in this case, act as counter-weights for each other.

It will not be necessary, in a case like this latter, for the person who controls the equilibrium of the several carriages, to be located upon the top, or even upon one of the carriages at all, as, by means of the connecting-rods and levers, he may well maintain their

equilibrium if he is standing or walking upon the ground.

Having now described the principle and operation of my invention,

What I claim as new, is—

A velocipede, connected with a truck, acting as a counter-weight, as set forth, to operate under control of the rider, as described.

J. H. IRWIN.
